UNITED STATES PATENT OFFICE.

FRIEDRICH CARL VOM BRUCK, OF DUSSELDORF, GERMANY, ASSIGNOR, BY MESNE ASSIGNMENTS, TO THE FIRM STANLEY WORKS GESELLSCHAFT MIT BESCHRÄNKTER HAFTUNG, OF GERMANY.

UNIVERSAL LOCK.

Application filed September 1, 1921, Serial No. 497,811, and in Germany January 28, 1919.

(GRANTED UNDER THE PROVISIONS OF THE ACT OF MARCH 3, 1921, 41 STAT. L. 1313.)

The object of the invention is to provide a lock which is chiefly adapted to be used for furniture in all possible cases and which inclusive of the key with the aid of the simplest means can be produced in an exceedingly accurate and cheap manner. In order to solve the problem according to the invention several provisions have been made.

Firstly the lock has been made suitable to act as a right- and left-hand lock and this is preferably achieved by providing an obstacle which can easily be moved to and fro for preventing a pushing through of the key.

This obstacle according to the invention consists of a ring which can easily be made to slide along the sleeve of the key.

Furthermore according to the invention, the lock by means of special ledges can be made to be used as a mortise lock or as a rabbed—or flush lock.

In addition thereto in accordance with the invention a nut turnable with a locking of the latch has been provided, said nut enabling the bolt-lock to be used at the same time as a bar-lock.

Through the use of the slideable obstacle the use of pipe-keys may be dispensed with and keys with uncurved bits may be employed.

The lock-latch according to a further part of the invention is formed in such a manner that in a U-shaped latch-head a filling piece is inserted and rigidly connected to the latch-head preferably by providing projections or recesses on the filling piece or latch-head respectively which by means of pressing are rigidly united with each other.

The lock-latch according to the invention is suitably guided on tongues stamped out from the lock frame, said tongues running preferably in the direction of displacement of the lock-latch.

The tumblers are also according to the invention in an exceedingly simple manner connected to their springs by first stamping the tumblers inclusive of a slot ending with an enlargement and by inserting a spring having a bent up portion into said slot and uniting it with the tumbler by pressing the slot together.

Also the key-sleeve is according to the invention produced in a most simple manner by

telescoping two or more sleeves of different lengths made of sheet iron which in the proper position to each other are held by a simple punching, whereby suitably one of the sleeves is fitted with a bore for receiving the punched part of the other sleeve.

Upon the accompanying drawing one mode of carrying out the invention is shown, in which

Fig. 1 is a side view of a lock placed as a mortise lock in a lock plate specially fitted with a ledge and with a casing lid removed,

Fig. 1^a, a plan of the lock with ledge, shown in Fig. 1,

Fig. 1^b, the plan of a latch with latch head,

Fig. 2 the view of the lock shown in Fig. 1 but reversed and with placed-on case-lid, so that the lock-latch projects to the right instead of to the left, Fig. 2^a being an end view of the mortise face plate,

Fig. 3, is a section along the line A—B of Fig. 1,

Fig. 4, a section along the line C—D of Fig. 2,

Fig. 5, a section through the key shaft,

Fig. 6, the longitudinal section of a key sleeve,

Fig. 6^a, a cross section along the line E—F of Fig. 6,

Fig. 7 shows a tumbler according to the invention and the tumbler spring previous to their being united with each other.

The lock casing a_1, a_2 , is in Figs. 1 and 1^a connected to a special plate b which is fitted with a ledge c so that the lock in this form may be used as a rabbeted lock.

In Fig. 2 the lock plate b according to Fig. 2^a has no side prolongation, so that in this case the lock may be used as a mortise lock.

In Fig. 3 the key d has been inserted into the lock from the left and in Fig. 4 from the right. Thus the lock is used in one case as a right hand and in the other case as a left hand lock.

In order to prevent a pushing-through of the key when the lock is being used as a right- or left-hand lock, a ring e is shown which may be made to slide on the key sleeve from the right hand and to the left hand end and reversely.

The key-bit is fitted with a groove g for the ring e , so that the bit can be made to act

with its full width on the tumblers and latches and in addition thereto may act as a guide to the key on the ring.

The latch plate *h* is fitted with teeth *i* which mesh with a toothed wheel *k*. The toothed wheel *k* is rigidly connected to a nut *l* through which a spindle pin may be passed that is adapted to operate members not shown, such as sliding bars or rods mounted 10 on a door, the ends of the bars being made to engage with the door frame and thus lock the door or the like when the key is turned.

The key-shaft according to the invention is provided with a strengthening rib *m* which 15 imparts a considerable strengthening effect to the thin key-shaft which owing to the dispensing of the pipe-key may be used especially in a right- and left-hand lock. Particularly with this key it is possible to produce it 20 in one preliminary and one finished form pressing from a form piece stamped from strong sheet iron, and preferably preliminarily scrubbed in a rotating drum containing a solution of acid. Hereby an exceedingly 25 neat and cheap key is produced, the smooth and hard polish of it making it extraordinarily well able to resist the formation of rust.

The key-sleeve shown in Figs. 6 and 6^a is 30 formed of two telescoping parts *n*, *o*, bent from sheet iron into a tubular shape, one of them being shorter than the other and the longer one serving as a key guide in the lock casing. One part is fitted, with a hole *p* to 35 which the other part is fastened by way of a punching *q*.

In Figs. 1 and 2 the lock casing is fitted with two flat pieces or lugs *r* which when stamping the casing are simultaneously formed and which serve as a guide for the 40 latch. Preferably these lugs are arranged in such a manner that they extend in the direction of the displacement of the latch.

Claims.

1. In a lock, a key-sleeve, a ring slidable on said key-sleeve for preventing the key from being pushed through, substantially as described. 45
2. In a lock, a key-sleeve, a stop slidable on said key-sleeve, substantially as described.
3. In a lock, a ring slidable on a key sleeve, a key and in the bit of the key a groove corresponding to the height of the said ring. 50
4. In a lock, a case plate, a latch, and flats stamped from the case plate adapted to be enclosed by openings in the said latch so as to 55 guide the latter in being displaced.
5. In a lock, a case plate, a latch, and narrow flat pieces arranged in the direction of displacement of the latch stamped from the case plate adapted to be enclosed by openings 60 in the latch.
6. In a lock, a key sleeve formed out of a plurality of bent sheet iron pieces which are assembled by telescoping.
7. In a lock, a key sleeve formed out of a 65 plurality of telescoped sleeves of different lengths made of sheet iron.
8. In a lock, a key sleeve formed out of a plurality of telescoped sleeves of different lengths made of sheet iron connected to each 70 other by punching.
9. In a lock, a key sleeve formed out of a plurality of telescoped sleeves of different lengths made of sheet iron, and a hole in one of the sleeves adapted to receive a punching 75 of another sleeve.
10. In a universal lock, the combination with a casing having a plate whereby it is adapted to be used as a mortise lock, and means for fitting a ledge to the casing thereby 80 converting it into a rabbeted lock.

In testimony whereof I have affixed my signature.

FRIEDR. CARL VOM BRUCK.
